UNITED STATES PATENT OFFICE

168,307

RACK FOR RUBBER STAMPS OR THE LIKE

Andrew Lenard, Forest Hills, N. Y.

Application August 28, 1952, Serial No. 21,223

Term of patent 14 years

(Cl. D74—13)

To all whom it may concern:

Be it known that I, Andrew Lenard, a citizen of Hungary, residing at Forest Hills, in the county of Queens and State of New York, have invented a new, original, and ornamental Design for a Rack for Rubber Stamps or the like, of which the following is a specification, reference being had to the accompanying drawing, forming part thereof, in which:

Fig. 1 is a top plan view of a rack for rubber stamps or the like showing my new design.

Figs. 2 and 3 are end and side elevational views, respectively, of the rack;

Fig. 4 is a bottom plan view thereof; and

Fig. 5 is a perspective view of the rack on a slightly larger scale.

I claim:

The ornamental design for a rack for rubber stamps or the like, as shown.

ANDREW LENARD.
